(57) **CLAIM**

The ornamental design for a watch with earphones, as shown and described.

DESCRIPTION

FIG. 1 is a bottom perspective view of a watch with earphones showing my new design, where the watch component is shown with the earphones component removed for ease of illustration;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the watch with earphones where the earphones component is shown removed from the watch for ease of illustration;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top perspective view of the watch with earphones where the earphones component is shown positioned in the watch component; and,

FIG. 18 is an enlarged detail of the circled portion 18 in FIG. 1.

The dashed broken lines in the drawings show portions of the watch with earphones which form no part of the claimed

(Continued)

design. The dash-dot-dash broken lines show the bounds of the enlarged detail and form no part of the claimed design.

1 Claim, 18 Drawing Sheets
